CLAIM

The ornamental design for a file box, as shown and described.

DESCRIPTION

FIG. 1 is a perspective view of a file box showing my new design;

FIG. 2 is a front elevational view, the opposite side being a mirror image thereof;

FIG. 3 is a left end elevational view, the opposite right end elevational view being a mirror image thereof;

FIG. 4 is a top plan view thereof; and

FIG. 5 is a bottom plan view thereof.
